UNITED STATES PATENT OFFICE.

FREDERICK O. WIERTH, OF BROOKLYN, NEW YORK, ASSIGNOR TO QUEEN AUTOMATIC PHONOGRAPH CO., INC., OF NEW YORK, N. Y., A CORPORATION OF NEW YORK.

PHONOGRAPH ATTACHMENT.

Original application filed December 8, 1919, Serial No. 343,303. Divided and this application filed August 26, 1920. Serial No. 406,083.

This application is a division of application filed by me December 8, 1919, Serial No. 343,303, for "phonograph attachments." This invention relates to a phonograph attachment or mechanism for successively placing a number of phonograph or talking machine records on a talking machine platen or turn-table and performing automatically operations of parts of a talking machine. 10 By the invention a number of selections or records may be played in succession without requiring any manipulation or effort on the part of the person using the machine.

The invention moreover provides a device 15 wherein the sound box and stylus are automatically lifted from the record and the arm carrying the sound box shifted to one side of the turn-table to an out of the way position so that the face of the turn-table is free 20 to receive a record, or another record, said lifting of the sound-box and shifting of the arm taking place after the completion of the playing of a record. The invention preferably provides means for automatically sup- 25 plying or placing another record on the turn-table, after the sound-box has been lifted and the arm shifted and also preferably provides means for returning the arm to playing position and releasing or drop- 30 ping the sound-box to bring the stylus again into contact with a groove in the record.

The invention further provides means for 35 stopping the turn-table after the last record, or a desired number of records, has been played, and also means for locking and releasing the turn-table stopping means by the taking off and putting on of sound records upon the turn-table.

The invention also provides certain ad- 40 junctive means for carrying out with greater perfection the operation of the foregoing parts, such as means for braking or retarding the turn-table during a part of the time the stylus is removed from the record, means 45 for impositively locking the reproducer arm in its out-swung position, and means for assuring the replacing of the stylus at the proper position on the record.

The invention further provides a means 50 of the character described which may be arranged or adjusted for different size records.

An embodiment of the invention is illus- 55 trated in the accompanying drawings, wherein

Figure 1 is a top plan view of a portion of a phonograph showing my invention applied thereto and with the parts in a playing position.

Figure 2 is a cross-sectional view taken on 60 the line 2—2 of Figure 1.

Figure 3 is a view similar to Figure 1 but showing the reproducer arm thrown to its extreme outer position.

Figure 4 is a cross-sectional view taken on 65 the line 4—4 of Figure 3.

Figure 5 is a cross-sectional view taken on the line 5—5 of Figure 3.

Figure 6 is a side elevational view of the parts shown in Figure 1, but looking from 70 the right, i. e. in the direction of the arrow 6.

Figure 7 is a side elevational view of the parts shown in Figure 1 but looking from 75 the left, parts being omitted for the sake of clearness.

Figure 8 is an enlarged top plan view of certain parts of the mechanism shown in Figure 3 and showing the reproducer arm in 80 dotted lines and thrown to its extreme inner position.

Figure 9 is a top plan view of a portion of the mechanism shown in Figure 8 and in the position after all of the records have been 85 played.

Figure 10 is an enlarged cross-sectional view taken on the line 10—10 of Figure 8.

Figure 11 is a view similar to Figure 10 with the parts shown in another position.

Figure 12 is a side elevation of the re- 90 producer arm and part of the mechanism secured thereto.

Figure 13 is an enlarged horizontal cross-sectional view of the reproducer arm, showing the bearing plate for holding the same, 95 and part of the mechanism secured thereon.

Figure 14 is a side elevational detail view of part of the mechanism shown in Figure 13.

Figure 15 is a view similar to Figure 14 100 showing the parts in another position.

Figure 16 is a detail cross-sectional view taken on the line 16—16 of Figure 15.

Fig. 17 is an enlarged fragmentary detail

elevation, partly in section, illustrating the pivot 92 of the lever 90 shown in Fig. 1 and other figures.

Referring to said drawings, number 1 designates a talking machine turn-table or platen, driven by any usual or suitable mechanism, and 2 designates a sound-box of any suitable construction, having a stylus or needle 3, and carried by any suitable arm 4, conveniently a combined arm and sound conveyer. As here shown the arm 4 swings on a vertical axis 6 in a suitable swivel-coupling or support 7 and the sound-box is conveniently connected to the arm through a goose-neck tube 8 swiveled around a horizontal axis and permitting of the lifting of the sound-box to and from the sound record, designated by the letter X. The arm 4 is normally adapted to move on its axis 6 to a position at one side of the turn-table when the stylus is out of engagement with a groove in the sound record. Numeral 11 designates a centering pin on the turn-table for centering the records placed thereon.

Record support or magazine.—In starting to operate the machine, a sound record is placed over the pin 11 onto the turn-table 1. Means are provided for holding a number of records in position to drop successively one another, onto the turn-table after the first and succeeding records have been played. These means preferably comprise a pair of uprights 13, 14, having ledges or supports 16, 17, somewhat above the upper face of the turn-table for a stack of sound records X'. The centering pin 11 is preferably long enough to extend through one or more of the sound records in the stack resting on the uprights 13, 14, and springs 19 are conveniently provided at the sides of the pin 11 for retarding the descent of the record, when released from the stack, onto the turn-table. The uprights 13, 14, are conveniently mounted in slides 21, 22, in which they may be moved in and out from the axis of the turn-table to provide for records of different diameters, fastening screws 23 being provided for holding the said upright fast on the slides. The ledge 17 is formed upon an arm or lever 25 pivoted to the upright 14, and is adapted to be withdrawn from beneath the stack, as hereinafter explained, to release the lowermost record, said upright 14 also having thereon a pivoted arm 27 which is adapted to be moved under the next to the lowermost record, at the same time, or somewhat previous to the time the ledge 17 is moved from beneath the stack, the remaining records in the stack being supported during the time the ledge 17 is withdrawn, by the ledge 16 and the arm 27. The ledge 16 is preferably made slightly yieldable as by means of the spring 29, whereby the ledges are kept in closer contact with the edges of the record. A connection 31 is provided be-

tween the pivoted arms 25 and 27, the arrangement being such that when the upper end of the arm 27 moves inward, the upper end of the arm 25 moves outward and vice versa.

The arm 27 may be rocked in any suitable manner to release a record from the stack. For this purpose, a longitudinally slidable rod 33 may be provided, said rod being provided with a two-face cam 34, the end of the arm 27 projecting into the groove between the two faces of said cam, as shown in Figures 1, 3 and 7. The rod 33 may be moved back and forth by hand, if desired, or as is preferred, automatically by means carried by the reproducer arm 4. These means may comprise a lever 43 having a weight 47 on one end thereof, explained more fully hereinafter, carried by the said arm 4 which weight strikes within a spring fork 36 on the end of the rod 33, and pushes the rod 33 so as to rock the lever 27 to release a record, the said rod 33 being pulled in the opposite direction by the arm 4 when it is moved inward toward the turn-table, the spring arm 36 grasping the weight 47 until the rod 33 reaches the end of its movement. The weight separates from the spring fork 36, whereupon the arm 4 moves free of the rod 33. This latter movement of the rod swings the lever 27, to bring the parts in position to release another record.

Sound box lifting mechanism.—Attached to the arm 4 is a bracket 40, Figures 6 and 12. Pivoted in the bracket 40 as indicated at 42 is a lever 43 one arm 44 of which extends under the sound box 2, and the other arm 45 of which conveniently curves around the support 7 and is weighted, as indicated at 47. The weighted end 45 of the lever is normally held up by a supporting piece 49 moving to and fro beneath the lever 42 on a vertical pivot 50. For moving the supporting piece 49 from beneath the lever 42, there is provided a trigger mechanism 51 pivotally connected to the piece 49 as indicated at 52 and turning around the vertical pivot 50 of the supporting piece 49. The trigger 51 has a hooked end 55 passing up under one side of the supporting piece 49, and at its opposite end a lateral projection 53 adapted to strike against the centering pin 11 when the stylus nears the end of the record. Continued rotation of the record causes the trigger to turn on its pivot 50, finally withdrawing the supporting piece from beneath the lever 43, whereupon the weight 47 causes the end 45 to drop, thereby elevating the end 42, and lifting the sound box, together with the stylus carried thereby, from the sound record, thereby allowing the arm 4 to be swung to a position at one side of the turn-table, as indicated in Figure 3 and in a manner which will be described later.

A spring 60 engages the trigger to return it and to move the supporting piece 49 beneath lever 43, when the lever 43 is again lifted, which lifting may be by hand, or 5 preferably, automatically, as hereinafter explained.

A spring latch 65 (Figure 3) may be provided for holding the arm in its swung-out position, so that there will be no tendency 10 of the arm to rebound toward or upon the turntable after it swings outward.

Mechanism for swinging reproducer arm back over turn-table and lowering sound box onto record.—Numeral 70 designates a lever, 15 pivoted at 72, having a cam or inclined plane 74 at one end, (Figures 4, 6) and having an arm 76 extending inward under the turn-table 1, (Figure 8). Fixed upon the underside of the turn-table are cams 78, 79 and 80 20 (Figures 1, 3 and 8). When the reproducer arm 4 is over the record and the parts are in playing position, the lever 70 is in the position shown in Figure 1, the arm 76 being out of reach of the cams 79 and 80. When 25 trigger 51 operates to release the lever 43 and thereby to lift the sound-box 2, and allow the reproducer arm 4 to swing outward to the side of the turn-table (position Figure 3), a projection 85 (Figures 1 and 12) 30 on the lever 43 strikes against a shoe 87 on a leg 88 of a three legged lever 90, pivoted on vertical and horizontal axes, as indicated at 92, (see Figs. 1 and 8) when the said lever 43 falls under the actions of the weight 35 47, thereby turning the lever 90 on its horizontal axis and lifting its arms 95 and 96, the arm 95 having a projection or roller 98 which when lifted is brought into the path of the cam 78 on the underside of the turn-table. The mounting of the lever 90 is 40 shown in greater detail in Fig. 17, in which it will be seen that the lever 90 is mounted for oscillation about a horizontal pivot 292, and for oscillation about a vertical pivot 45 492, provided on the member 92 and extending into the member 392. When the cam 78 strikes against the grooved roller 98, the lever 90 is turned on its vertical pivot, bringing the arm 96 against the lever 70 50 (or a shoe 100 on the lever 70, Figures 1 and 8) thereby moving the lever around its pivot 72 to the position shown in Figure 8). The lever 70 has the lower end portion of the cam or inclined plane 74 provided with an up-standing finger 74' (see Figures 1, 3, 4 and 6). When the lever 43 has been released by the trigger 51, as previously described, it 55 falls behind the finger 74' and in the path of movement thereof, as shown in Figures 3 and 4. Now when the lever 90 is turned the finger 74' engages the side of the lever 43 thus swinging the arm 4 carrying the stylus and sound box to its outer position. 60 A spring latch (Figure 2) 99 serves to im- 65 positively lock the lever 70 in the position

shown in Figure 8, to which it has been moved by the arm 96. The projection 85 remains on the shoe long enough for the cam to effect the turning of the lever 90 on its vertical pivot and the movement of the end 70 74 of the lever 70 outward. After the projection 85 moves off of the shoe 87 and after the cam has disengaged the projection on the leg 95 the latter falls down out of the way of the cam 78. The lever 90 is 75 returned to initial position (i. e. the position shown in Figure 1) by any suitable means, as for example by the lever 70 when its end 74 is swung inward, as hereinafter explained.

The turning movement of the lever 70 80 brings its end 76 first into contact with the cam 79, and after a short intervening interval, into contact with the cam 80. The cam 79 moves the lever 70 around its pivot 72, causing the inclined plane 74 on its opposite 85 end to contact with the lever 43 carried on the reproducer arm 4 (the arm 4 having swung to its outer position beyond the turn-table by this time, and a record having meanwhile dropped from the magazine on to the 90 turn-table) and swing the reproducer arm 95 inward to a position where the stylus is over the beginning of the sound-groove of the record. A pin or projection 103 (Figures 1, 12, 13, 14, 15) on the lever 43 fitting in a slot or groove 105 in a guide 107 alongside the swivel coupling 7 of the reproducer arm, prevents the lever 43 from being turned on its pivot 42 (see position A, Figure 15). Consequently the weighted end of the lever 100 remains lowered, and its opposite end remains elevated, the sound box being thereby prevented from lowering and the stylus kept out of contact with the record during the inward swinging movement of the reproducer arm 4. When the projection 103 reaches the end of the groove 105 (corresponding to the position of the stylus over the beginning of the record groove) the pin 103 has entered a groove in a pivoted forked 110 piece 109, which forked piece, when turned to the position shown in Figure 14, prevents further movement of the projection 103 (and consequently of the reproducer arm 4) around the axis 6, but permits upward movement of the projection 103. (See position B, Figure 14.) The upward movement of the projection 103, with the consequent turning of the lever 43 on its pivot 42 and lowering of the sound-box and contacting 115 of the stylus with the record, occurs when the cam 80 comes into contact with the end 76 of the lever 70, causing the lever 70 to resume its turning movement around the pivot 72, and the inclined plane 74 to lift 120 the end of the lever 43 carrying the pin 103. Playing of the sound record thereupon begins.

When the weighted end of the lever 43 is 125 lifted by the inclined plane 74, the trigger 130

piece 51 is allowed to turn under the influence of spring 60, and thereby bring the supporting piece 49 beneath the lever 43, the weighted end of the lever 43 being thereby prevented from turning the lever 43 on its pivot 42 when the reproducer arm is swung or fed inward by the engagement of the stylus in the spiral groove of the record. Moreover when the lever 43 is lifted by the 10 inclined plane 74, the pin 103 is lifted out of the forks of the forked piece 109, into line with a tappet 111 on a pivoted latch 113, position C, Figure 14. The forked piece 109 has a tail-piece 115 which is caught and held 15 by the latch 113 when the forked-piece is lifted to upright position. The forked piece is weighted as indicated at 117 and bears against a resilient stop 119 as shown in Figure 15, so as to normally hold the mouth of 20 the fork on a level with the groove 105. When the pin 103 on the lever 43 comes into contact with the tappet 111 (as the reproducer arm moves over the record during playing) the tail-piece 115 of the forked-piece 25 109 is released. The resilient stop 119 yields in order to permit the pin 103 to pass the forked piece 109 in entering the groove 105, see the dotted line position, Figure 15.

Means for retarding turn-table while reproducer arm is being swung to side of turn-table.—During the time the reproducer arm is moving to a position at the side of the turn-table, the stylus being lifted from the record, it is desirable to apply a retarding 30 force on the turn-table 1 to prevent the turn-table from speeding owing to the lessened resistance to its rotation. To this end, the lever 70 may be provided with a resilient arm 121 carrying a brake 123 (Figures 1, 3 and 8) adapted to bear on the periphery of the turn-table 1. The resiliency of the 35 spring-arm 121 determines the braking force of the brake, and is not so great as to stop the rotation of the turn-table. After the reproducer arm is swung to the position at the 40 side of the turn-table, it is desirable to release the turn-table from the brake 123, in order that the full force of the motor may be effective in returning the reproducer arm 45 to playing position (the motor acting through the cams 79 and 80, lever 70 and inclined plane 74). For this purpose there may be provided an arm 130, pivoted at 131, and having an upstanding part 133 adapted 50 to contact with the reproducer arm 4 as it moves outward (conveniently through a resilient arm 135 on the lever 43) and bring a boss 137 on said arm 130 against a tail-piece 139 attached to the brake 123, and thereby remove the brake 123 from the turn-table, as shown in Figure 3.

Mechanism for stopping turn-table.—When all of the records have been played, it is desirable to stop the turn-table. The 55 means for this purpose may comprise a

bell-crank pivoted lever 150, having a brake-shoe 151 therefor, and having a notched arm 152, having a number of notches corresponding to the number of records to be played. See Figures 1, 3, 8, 9, 10, 11. The lever 150 70 is normally pulled toward the turn-table by a spring 154. The lever 150 is held out of braking contact with the turn-table until all the records are played, by a pawl 156, pivoted at 157, and having a tail 158, adapted to be engaged by a stepped pawl 160 having a number of steps or notches 161 corresponding to the number of notches on the lever 150. The stepped pawl 160 is pivotally connected to the lever 90 and a spring 163 may 75 be provided for holding it down. When the lever 90 is turned around its vertical pivot 92 (by the cam 78 as hereinbefore explained) the stepped pawl 160 is pressed forward into contact with the tail 158 of the pawl 156, 80 thereby turning the pawl 156 on its pivot, the amount of movement imparted to the pawl 156 being sufficient to cause it to move from one notch in the lever 150 to another. Upon the return movement of the lever 90, 85 the stepped pawl 160 is carried back to its initial position the next forward notch 161 thereof dropping behind the tail 158 during the return movement. A beveled face 163' 90 on the pawl 160 striking against a projection 165 lifts the pawl 160 at each oscillation so that when the pawl drops off of the projection 165, any one of the notches on steps 161 has been lifted high enough to fall upon the tail 158 of the pawl 156. At each oscillation of the lever 90 the pawl 156 moves forward one step or notch on the lever 152, and, after the last record has been played, it moves off the end of the notched arm 152 of the lever 150, allowing the spring 154 to 95 pull the brake shoe 151 against the turn-table and stop it.

Mechanism for locking turn-table stopping means in stopping position.—Means may be provided for automatically locking the stopping means in stopping position. These means may comprise a rock-shaft 170 extending under the turn-table and having an arm 171 pressed upwardly by a spring 172, and an arm 174 with a rounded part 175. (Figure 5.) The arm 171 is normally held against the upward pressure of the spring 172 by means of a spring pressed latch 177. After the pawl 156 passes off of the notched arm 152 it strikes the latch 177 and moves 100 out of engagement with the arm 171 which arm 171 is pressed upwardly by the spring 172 rocking the shaft 170 and allowing the arm 174 beneath the turn-table to rise. The turn-table is preferably provided with a slot 180 (Figures 1 and 3) into and through which the arm 174 may rise when all the records have been removed from the turn-table, the arm 171 being raised behind the notched arm 152 and preventing the arm 152 105 110 115 120 125 130

from being turned to release the turn-table while no record is on the turn-table. The placing of a record on the turn-table depresses the arm 174, rocking the shaft 170 and carrying the arm 171 below the arm 152, whereupon the lever 152 may be turned with its pivot to release the turn-table, the pawl 156 moving back to its initial position in the first notch in the arm 152, under the pressure of its spring and the latch moving forward over the arm 171, thereby resetting the stop actuating and stop locking mechanism. A stop 181 may be provided for limiting the up-position of the arms 171 and 174.

15 *Mechanism for adjusting the device for different diameter records.*—In order that the stylus may be dropped into the beginning part of records of different diameter, as for example records of 10 and 12 inch diameter the guide 107 is carried by a slidable part or plate 190 (Figures 13, 14, 15, 16). A clamp-screw 191 serves for holding the plate 190 in its different positions. An indicator 192 may serve for indicating the position of the guide 107 and plate 190 for various size records. When the guide 107 is set for 12 inch records, for example, the pin 103 on the lever 43 will reach the end of the slot 105 in the guide 107 at a greater angular distance from the centering pin 11 than for 10 inch records. As the inclined plane 74 rocks the lever 43 at the point where the pin 103 leaves the slot 105 (as hereinbefore explained) lowering its end 44, the sound-box 2 will be lowered at a point which will be more radially distant from the centering pin 11 than for 10 inch records, as is required.

40 *General description of operation.*—When a record is placed on the turn-table the arm 174 is depressed moving the arm 171 from behind the bell lever 150 and allowing this lever to be turned to release its brake-shoe 151 from the turn-table, when it is desired 45 to start the talking machine. A plurality of records are placed on the ledges 16, 17 above the turn-table.

When the turn-table is released from the brake 151, the cams 79 and 80 on the under-side of the turn-table, actuate the lever 70 to move the reproducer-arm 4 from the position shown in Figure 3 to a position over the margin of the sound-record. Here the lever 43 is turned by the inclined cam 74, lowering its end 44 and carrying with it the sound-box 2 and bringing the stylus 3 into contact with the beginning part of the sound record.

By adjusting the plate 190 carrying the 60 guide 107 the lever 43 may be made to lower the sound-box at different distances from the center-pin 11 in accordance with the diameter of the record. The uprights 13, 14 are also adjusted for the different size 65 records.

After the stylus 3 reaches the end part of the record the final spirals bring the trigger 51 against the centering-pin 11, causing the trigger to withdraw the supporting-piece 49 from beneath the lever 43. When the supporting-piece 49 is removed the weight 47 causes the lever to rock on its pivot, lifting the sound-box 2, and allowing the reproducer arm 4 to be swung to one side by its swinging mechanism. 75

When the weight 47 rocks the lever 43, a projection 85 thereon strikes the shoe 87 on a lever 90, raising the ends 95 and 97 of said lever around the horizontal pivot and bringing a roller 98 thereon into engagement with a cam 78 on the turn-table which moves the lever 90 on its vertical axis, causing it to turn the lever 70 to the position shown in Figures 3 and 8.

A brake shoe 123 carried by the lever 70 bears on the turn-table to retard its movement during the time the reproducer arm is moving outward.

In the final part of its outward movement, the reproducer arm 4 strikes a lever 130 moving it to release the brake 123 and the weight 47 pushes the rod 33 causing the cam 34 thereon to rock the levers 27 and 25 to release a sound-record from the underside of the stack above the turn-table, the released record falling onto the turn-table during the time the reproducer arm 4 is to one side of the turn-table (position Figure 3).

The cams 79 and 80 then successively come in contact with the end 76 of the lever 70 turning it around its pivot and moving the reproducer arm inward toward the turn-table.

When the pin 103 on the lever 43 reaches the end of the slot 105 in the guide 107 the inclined plane 74 on the lever 70 raises the end 45 of the lever 43 and lowers the sound-box 2 to bring the stylus into contact with the sound record, whereupon the playing of the new record begins and a new cycle of 110 operations begins.

When the reproducer arm 4 begins its inward movement the rod 33 is returned to its original position through the action of the spring-arms 36 engaging the weight 47. 115 In returning to such position the two-face cam 34 effects the resetting of the levers 25 and 27.

The inward movement of the end 74 of the lever 70 returns the lever 90 to initial 120 position.

Each time the lever 90 is oscillated a stepped pawl 160 carried thereby advances a pawl 156 one notch on the notched arm 150. When all of the records have been 125 played and the pawl 156 moved beyond the end of the arm 152 of the lever 150, the lever 150 is released, and moved into contact with the turn-table, stopping it.

The removal of the records from the turn- 130

table allows the arm 174 to rise through a slot 180 in the turn-table, thereby turning the rock-shaft 170 and lifting an arm 171 behind the lever 150 and preventing it from being turned to release the turn-table until a record is again placed on the turn-table.

It is evident that many parts and elements hereof may be used separately from the other part and elements.

10 The inventive ideas herein set forth may include other embodiments than that herein specifically illustrated and described.

What I claim is:—

1. A device of the character described 15 comprising in combination, a turntable and a stop therefor, means automatically called into action after the playing of each of a number of records upon said turntable for supplying another record to said turntable, 20 said stop comprising a brake, means temporarily holding said brake out of contact with said turntable, said last mentioned means comprising a step-by-step actuated detent, and means moving said detent one step after 25 the playing of each record, said detent after a predetermined number of steps releasing said brake.

2. A device of the character described comprising a turn-table and a stop therefor, 30 said stop comprising a brake, means temporarily holding said brake out of contact with said turntable, means for locking said brake in contact with the turntable, and means actuated by a record on the turn-table 35 for moving said locking means to unlock said brake, said first mentioned means comprising a step-by-step actuated detent, and means moving said detent one step after the 40 playing of a record, said detent after a predetermined number of steps releasing said brake.

3. A device of the character described comprising a turn-table and a stop therefor, said stop comprising a brake, means 45 temporarily holding said brake out of contact with said turntable, said means comprising a step-by-step actuated detent, and means moving said detent one step after the playing of a record, said detent after a predetermined number of steps releasing said 50 brake, said detent moving means comprising a lever and a cam on the turn-table for turning said lever, and means for lifting said lever into contact with said cam to cause 55 operation of said detent moving means.

4. A device of the character described comprising a turn-table and a stop therefor, said stop comprising a brake, means temporarily holding said brake out of contact 60 with said turntable, said means comprising a step-by-step actuated detent, and means moving said detent one step after the playing of a record, said detent after a predetermined number of steps releasing said 65 brake, said detent moving means comprising

a lever and a cam on the turn-table for turning said lever, and means for lifting said lever into contact with said cam to cause operation of said detent moving means, said lifting means comprising a reproducer arm. 70

5. A device of the character described comprising a turn-table and a stop therefor, said stop comprising a brake, means temporarily holding said brake out of contact with said turntable, said means comprising 75 a step-by-step actuated detent, and means moving said detent one step after the playing of a record, said detent after a predetermined number of steps releasing said brake, said detent moving means comprising 80 a lever and a cam on the turn-table for turning said lever, and means for lifting said lever into contact with said cam to cause operation of said detent moving means, said lifting means comprising a reproducer arm, 85 a lever pivoted thereon, and a trigger, said trigger being moved by said reproducer arm when it reaches the end part of a record to release said lever on the reproducer arm to lift said detent-moving lever. 90

6. A device of the character described comprising a turn-table and a stop therefor, said stop comprising a brake, means temporarily holding said brake out of contact with said turntable, said means comprising 95 a step-by-step actuated detent, and means moving said detent one step after the playing of a record, said detent after a predetermined number of steps releasing said brake, said detent moving means comprising 100 a lever and a cam on the turn-table for turning said lever, means for lifting said lever into contact with said cam to cause operation of said detent moving means and a stepped pawl carried by said lever. 105

7. A device of the character described comprising a turn-table, means for automatically placing each of a series of records upon said turn-table after the preceding record thereon has been played, means for automatically playing the records in succession and means coacting therewith for automatically engaging the turn-table and stopping said playing means when the last record has been played. 110

8. A device of the character described comprising a turn-table, means for automatically depositing each of a series of records upon said turntable after the preceding record thereon has been played, means for automatically playing the records in succession and means coacting therewith for automatic turning of said turn-table after the playing of successive records and for engaging the turn-table and stopping 115 said playing means when the last record has been played.

9. A device of the character described, comprising a turn-table, a reproducer-carrier, means for stopping said turn-table, and 120 125 130

means for actuating said stopping means, said actuating means comprising a part adapted to be moved into position to be actuated by a part on and below said turn-table, and means on said reproducer carrier, adapted to move said actuating part into said position to be actuated by said turn-table part.

10. A device of the character described, comprising a turn-table, a reproducer-carrier, means for stopping said turn-table, and means for rendering said stopping means operative, said last mentioned means comprising a part adapted to be moved into position to be actuated by a part on said turn-table, said turn-table being provided with said last mentioned part and means on said reproducer carrier adapted to move said first mentioned part into said position to be actuated by said turn-table part, and a step-by-step moving part adapted to be actuated by said first mentioned part, and adapted at the end of the series of steps to render said stopping means operative.

25. 11. A machine of the character described comprising in combination, means for playing records, means controlled by said playing means for successively supplying a series of records to said playing means, means controlled by said playing means for stopping said playing means after the playing of said series of records, means for rendering said stopping means operative including a step-by-step moving part adapted to move one step after the playing of each record and to render said stopping means operative at the end of its series of steps.

40. 12. A machine of the character described comprising in combination, means for playing records, means controlled by said playing means for supplying a plurality of records to said playing means, said second named means including supporting means for a series of records and means for causing each of the records to drop to playing position after the preceding record has been played, and means controlled by said playing means for stopping said playing means after the playing of the last record.

45. 13. A machine of the character described comprising in combination, means for playing records, means controlled by said playing means for supplying a plurality of records to said playing means, means controlled by said playing means for stopping said playing means after the playing of the last record, and means preventing the release of said stopping means in the absence of a record in position to be played.

60. 14. A device of the character described, comprising a turn-table, means for playing records, means controlled by said playing means for supplying a plurality of records to said playing means, said second mentioned means including means for supporting a plu-

rality of records in a stack above the turn-table and means for delivering the records one after the other to the turn-table from the bottom of the stack, and means controlled by said playing means for automatically stopping said playing means after the playing of the last record.

15. A device of the character described, comprising a turn-table, means supporting said turn-table for rotation but constraining it against movement in an axial direction, means for playing records, means controlled by said playing means for supplying a plurality of records to said playing means, said second mentioned means including means for supporting a plurality of records in a stack above the turn-table and means for delivering the records one after the other to the turn-table from the bottom of the stack, and means controlled by said playing means for automatically stopping said playing means after the playing of the last record.

16. A device of the character described, comprising a turn-table, means for playing records, means controlled by said playing means for supplying a plurality of records to said playing means, said second mentioned means including means for supporting a plurality of records in a stack above the turn-table and means for delivering the records one after the other to the turn-table from the bottom of the stack, and means controlled by said playing means and including a brake for automatically stopping said playing means after the playing of the last record.

17. A device of the character described, comprising a turn-table, means including a sound-box mounted for vertical and lateral movement with respect to the turn-table for playing records, means controlled by said playing means for supplying a plurality of records to said playing means, said second mentioned means including means for supporting a plurality of records in a stack above the turn-table and means for delivering the records one after the other to the turn-table from the bottom of the stack, and means controlled by said playing means and including a brake for automatically stopping said playing means after the playing of the last record.

18. A device of the character described, comprising a turn-table, means for playing records, means controlled by said playing means for supplying a plurality of records to said playing means without lowering said turn-table, said second mentioned means including means for supporting a plurality of records in a stack above the turn-table and means for delivering the records one after the other to the turn-table from the bottom of the stack, and means controlled by said playing means for stopping said playing means after the playing of the last record.

19. A device of the character described,

- comprising a turn-table, means for playing records, means controlled by said playing means for supplying a plurality of records to said playing means, said second mentioned 5 means including means for supporting a plurality of records in a stack above the turn-table and means for delivering the records one after the other to the turn-table from the bottom of the stack, and means controlled 10 by said playing means and including a turn-table brake for automatically stopping said playing means after the playing of the last record.

- 15 20. A device of the character described, comprising a turn-table, means including a sound-box mounted for vertical and lateral movement with respect to said turn-table for

playing records, means controlled by said playing means for supplying a plurality of records to said playing means without lowering said turn-table, said second mentioned means including means for supporting a plurality of records in a stack above the turn-table and means for delivering the records one after the other to the turn-table from the bottom of the stack, and means controlled by said playing means and including a turn-table brake for automatically stopping said playing means after the playing of the last record.

Signed at New York in the county of New York and State of New York this 30th day of July, A. D. 1920.

FREDERICK O. WIERTH.
